UNITED STATES PATENT OFFICE

151,041

DESIGN FOR A PORTABLE ALTAR

Rudolph T. Gudell, North Chicago, and George
A. Feeny, Chicago, Ill.

Application May 14, 1947, Serial No. 139,036

Term of patent 14 years

(Cl. D29—23)

To all whom it may concern:

Be it known that we, Rudolph T. Gudell and George A. Feeny, both citizens of the United States and a resident of North Chicago, in the county of Lake and State of Illinois, and a resident of Chicago, in the county of Cook and State of Illinois, respectively, have invented a new, original, and ornamental Design for a Portable Altar, of which the following is a specification, reference being had to the accompanying drawing forming a part thereof, and in which:

Fig. 1 is a perspective view of a portable altar, showing our new design;

Fig. 2 is a side elevational view of the same.

We claim:
The ornamental design for a portable altar, as shown,

RUDOLPH T. GUDELL.
GEORGE A. FEENY.
